UNITED STATES PATENT OFFICE.

EUGENE R. CARICHOFF, OF SCHENECTADY, NEW YORK, ASSIGNOR TO GENERAL ELECTRIC COMPANY, A CORPORATION OF NEW YORK.

SYSTEM OF SELECTIVE CONTROL.

Application filed January 4, 1922. Serial No. 526,885.

To all whom it may concern:

Be it known that I, EUGENE R. CARICHOFF, a citizen of the United States, residing at Schenectady, in the county of Schenectady, State of New York, have invented certain new and useful Improvements in Systems of Selective Control, of which the following is a specification.

My invention relates to an improved selective control system whereby any desired portion of a plurality of separate paths from the supply conductor may be selected and established at will. The invention has a particular application in the selective control of the direction of operation of an electric vehicle from a point remote from the vehicle, although the invention is not necessarily limited to such use.

One of the objects of the invention is to provide an arrangement whereby after the particular portion of the paths for the current from a single supply conductor has been selected and established, the unintentional establishment of another portion of the paths is prevented.

My invention is particularly directed to improvements in the system of selective control, for which John Eaton filed an application for patent, Serial No. 526,983, filed January 4, 1922, which is assigned to the same assignee as this invention.

In general, the system of selective control, disclosed and claimed in the said Eaton application, comprises electro-responsive switch mechanism energized from the supply conductor for establishing the particular portion of the paths for the current from the conductor, and the selective operation of the electro-responsive switch mechanism is controlled by means of a selector relay which is controlled responsively to the potential of the supply conductor. The potential of the supply conductor is controlled by means of a controller located at a remote point. While the Eaton system is entirely operative and practical for the ordinary conditions encountered in the service for which the system is intended, difficulties are encountered due to unusual or certain special conditions. Thus, in case the full potential of the supply conductor is rendered ineffective to control the selector relay, due for instance, to the presence of a high resistance condition such as sleet or dirt on the supply conductor, dirt on the

track return when the system is used for the control of an electric vehicle, or the trolley of the vehicle temporarily leaving the trolley wire, the selector relay may not function exactly as intended, and may select one portion of the paths for the current when it is desired that another portion be selected. Another condition to be provided against is encountered when the path established from the supply conductor is opened, either intentionally or unintentionally. In such a case, it may happen that a gradually decreasing current from the supply conductor may cause the unintentional operation of the selector relay, and in case, for example, the control system be used to govern the direction of operation of an electric vehicle, the vehicle may be unintentionally reversed at such a time.

My invention provides improved means whereby this unintentional establishment of any one of the particular portions of the paths from the conductor is prevented.

In carrying my invention into effect in one form, I have provided electromagnetic means under the control of the potential of the supply conductor for preventing the operation of the selector relay after it has operated to select a particular path for the current and so effectively lock the relay in the position to which it has been operated and thereby prevent any unintentional operation of the same.

For a better understanding of the invention, reference is had to the accompanying drawing wherein I have illustrated an embodiment of my invention in the selective control for an electric vehicle from a point remote from the vehicle. Referring to the drawing, the electric vehicle has not been shown since that would add nothing to an understanding of the invention. The electric motor for driving the vehicle has an armature 10, a commutating field 11 and a series field 12. The direction of operation of this motor and the vehicle driven thereby is controlled by means of the electro-responsive reversing switch mechanism which comprises the double-pole electromagnetically operated switch or contactor 13 for the forward direction of operation and the double-pole contactor 14 for the reverse direction of operation. These direction contactors are suitably interlocked by means of the pivoted locking bar 15 so that only one

2
contactor may close at a time. The direction contactors 13 and 14 are provided for establishing separate paths for the current from the single supply conductor 16 with 5 which the trolley 17 of the vehicle is normally in engagement.

The selective operation of the direction contactors 13 and 14 is under the control of the selective relay 18. This relay comprises 10 a single switch member 19 which is under the joint control of the two "series" lockout type electromagnets 20 and 21. These electromagnets are each of the well-known type which is magnetically held in a biased position when the current in the winding of the electromagnet is above a predetermined value and which causes a movable member of the electromagnet to operate to another position and be magnetically held therein 15 20 when the current in the winding of the electromagnet is below a predetermined value. The relays are diagrammatically illustrated as of the type fully described in Letters Patent to Harry R. Canfield No. 1,344,260, dated June 22, 1920, although my invention is not necessarily limited to the particular type of "series" relay disclosed in this application and covered broadly by the said Canfield patent. The electromagnet 20 is 25 30 provided with a movable magnetic member or plunger 22 which is adapted to be brought into engagement with the switch member 19 to tilt the same, and the electromagnet 21 is provided with a plunger 23 for 35 40 tilting the switch member 19 in the opposite direction. The electromagnet 20 is provided for selecting the forward direction of operation and the electromagnet 21 is provided for selecting the reverse direction of vehicle operation.

The selector relay 18 is controlled by means of a reversing controller at 24 which is also provided with means for controlling the acceleration and the speed of operation 45 of the motor vehicle after the selected path for the current has been established by the operation of either one or the other of the direction contactors 13 and 14. The controller 24 is adapted to control the comparatively high resistance resistors 25 and 26 50 for controlling the selective operation of the relay 18. The accelerating and speed varying resistor 27 is adapted to be short circuited step by step by means of suitable 55 contact segments on the controller for both forward and reverse operation. The last section of this resistor 27 is controlled by the series contactor 28 which is provided for the purpose of insuring that at least a portion 60 of the resistor 27 will be included in the motor armature circuit until the current taken by the motor has dropped to a predetermined value. The "series" lockout type contactor 28 is diagrammatically illustrated 65 as of the type fully disclosed in Letters Pat-

ent to Edwin J. Murphy No. 1,352,307, dated September 7, 1920.

The unintentional operation of the selector relay is prevented by electro-responsive means comprising the electromagnet 29, the winding of which is permanently connected to the supply conductor 16 through the trolley 17. This electromagnet is provided with a magnetic movable member 30 which serves as a locking detent for the pivoted switch member 19. The magnetic locking member 30 is normally biased out of engagement with the arm 31 secured to the switch member 19, and is arranged so that when the electromagnet is energized, the locking member makes engagement with this arm 31 to prevent the operation of the switch 19 to its other position until after the electromagnet 29 is deenergized. Although the general control system is disclosed and claimed broadly in the aforesaid Eaton application the particular form of selector relay which I have selected for the purpose of illustrating my invention and the connection of this relay in a selective system of control is disclosed and claimed in an application for patent filed by Charles B. Connelly, Serial No. 546,776, filed March 25, 1922, and assigned to the same assignee as this invention.

As thus constructed and arranged, the operation of my invention is as follows: It is believed that an understanding of the invention will be more readily had by indicating generally a particular system in which the various devices are intended to operate at selected voltages or current values, and I shall therefore describe my invention in this manner, but would have it understood that my invention is not necessarily limited to the following relation of the various parts, but that the particular example is given for the sole purpose of obtaining a quick understanding of the invention. Let it be assumed that the voltage of the source of supply indicated at 32 is 250 volts and that the operating electromagnets of the direction contactors 13 and 14 will be energized to close at any voltage above 230 volts, but not at any lower voltage. Assume that it is desired that the motor vehicle operate in the forward direction. The switch member 19 of the selector relay 18 is in the proper position for this direction of operation, so that by moving the reversing controller 24 from its off position toward the right to its first operative position the "series" windings of the relays 20 and 21 will be connected from the source of supply through a circuit including the high resistance selector resistor 26, the accelerating resistance 27, supply conductor 16, trolley 17, through the windings of the electromagnets 20 and 21, the armature 10 of the electric motor and commutating field 11 to the ground return, 120 125 130

which is indicated as the return conductor for the system. The value of the resistor 26 will be such that the potential of the supply conductor 16 will be reduced to such a value that substantially 2 amperes will flow through the windings of the relays. This value of current will cause the operation of the plunger 22 of the electromagnet 20, but the plunger 23 of the electromagnet 21 will be magnetically held in its biased position. The operation of the plunger 22 produces no effect on the switch member 19, for the reason that it is already in the proper position for selecting the forward direction of operation. The voltage of the supply conductor 16 will be below 230 volts, the value at which the direction contactor 13 will be energized to close, and this contactor will not be energized to close until the controller 24 is advanced to its second operative position, at which the resistor 26 will be excluded from the circuit. When this happens, the potential of the supply conductor 16 will be increased above 230 volts and the direction contactor will be energized to close through the switch member 19 of the selector relay. When the contactor 13 closes, one path for the motor current is closed from the plus side of the source of supply 32, through the accelerating resistor 27, supply conductor 16, trolley 17, upper contacts of the contactor 13, through the series field 12 of the motor, through the series holding winding 33 associated with the lower contacts of the contactor 13, lower contacts of contactor 13, through the motor armature 10 and commutating field 11 to the ground return. The locking electromagnet 29 for the selector relay will be substantially simultaneously energized to attract its locking member 30 with the closing of the direction contactor 13. The winding of the locking electromagnet 29 and the magnetic circuits of this electromagnet are designed so that the locking member 30 will not be attracted into locking engagement with the arm 31 until a voltage is applied to the winding which is above the voltage at which the relays 20 and 21 will operate so as not to interfere with the operation of the relays under normal conditions, but after the locking member 30 is operated to the attracted position it will be maintained in the attracted position even though the current through the winding of the electromagnet drops to a very low value.

In order to accelerate the electric motor, the controller 24 is advanced toward the right through its successive operating positions until the final position has been reached at which the winding of the "series" lock-out type contactor 28 is included in circuit. When the current taken by the motor has dropped to a predetermined value this series contactor will close and short cir-

cuit the final section of the resistor 27, thereby connecting the motor directly across the source of supply. If for any reason the effective potential applied to the motor and applied to maintain the direction contactor 13 closed should drop below the value at which the direction contactor 13 will open, the windings of the electromagnets of the selector relay are included in series with the motor armature, so that the current through these windings may drop to such a value that the plunger 23 of the electromagnet 21 will operate to endeavor to throw the switch member 19 to its opposite position. The locking electromagnet 29 is provided for taking care of conditions of this general nature. If, for example, the trolley 17 should temporarily leave the conductor 16 and draw an arc, the direction contactor 13 may open and in this case the relay windings are included in series with the arc, so that the relay may tend to select for the other direction of operation in such a condition. Another condition provided against by the locking electromagnet 29 is the drawing of an arc at the final segment of the controller 24 when the controller is returned to its off position. The establishment of such an arc at the controller for a small interval of time may cause the selector relay to attempt to operate and establish the connections for the opposite direction of rotation. Another condition provided against by the provision of the locking electromagnet is the presence of sleet or dirt on the trolley wire 16 or some high resistance condition on the track return for the vehicle.

It will be understood that in case it is desired to operate the motor vehicle in the reverse direction, the controller 24 is first returned to its off position. The direction contactor 13 will thereupon be deenergized and open, and the winding of the locking electromagnet 29 will be deenergized so as to release the locking member 30. In order to reverse the direction of motor operation, the controller 24 is moved from the off position toward the left to its first operative or selective position. Both of the high resistance resistors 25 and 26 are thereupon included in the circuit of the windings of the electromagnets 20 and 21 of the selector relay 18. The two resistors 25 and 26 will limit the value of current through the relay windings to 1 ampere, for example. With this value of current, the electromagnet 20 will not be sufficiently energized to operate its plunger 22, but the electromagnet 21 will be sufficiently energized to operate its plunger 23 and thereby tilt the switch member 19 so as to complete a circuit for the winding of the direction contactor 14. The value of current through the winding of the direction contactor 14 will be limited so that this contactor will not operate, and the value

of current through the winding of the locking electromagnet 29 will not be sufficient to cause the locking electromagnet to operate. When the controller 24 is moved to its second operative position to the left, substantially full potential is applied to the supply conductor 16, and the direction contactor 14 will be energized to close to establish the circuit for the motor from the supply conductor and the locking electromagnet 29 will be energized to attract the locking member 30 to prevent further unintentional operation of the selector relay. The path for the motor current will now be established from the source of supply through the accelerating resistor 27, the supply conductor 16, trolley 17, lower contacts of the direction contactor 14, through the series holding coil 34, through the motor field 12 in a direction opposite to that established by the closing of the direction contactor 13, through the upper contacts of the direction contactor 14, motor armature 10 and commutating field 11 to the ground return. The acceleration of the motor will be governed by short circuiting step by step the accelerating resistor 27. The locking electromagnet 29 will now prevent the unintentional operation of the selector relay in the same manner as that previously explained.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

40 What I claim as new and desire to secure by Letters Patent of the United States, is:—

1. The combination in a selective system of control of a supply conductor, electro-responsive switch mechanism for establishing a selected portion of a plurality of separate paths from the said conductor, an electro-responsive relay connected to the said conductor and operated responsively to the potential of the conductor for controlling the energization of the said switch mechanism to select the portion of the said paths from the said conductor to be established, and electro responsive means energized responsively to the potential of the said conductor for locking the said relay from further unintentional operation after the desired portion of the said paths has been selected.

2. The combination in a selective system of control of a supply conductor, electro-responsive switch mechanism for establishing a selected portion of a plurality of separate paths from the said conductor, an electro-responsive relay connected to the said conductor and operated responsively to the

current through the conductor for selecting the portion of the said paths from the said conductor to be established by the said switch mechanism, a controller for connecting the said conductor to a source of supply and for limiting the value of current through the conductor, and means for locking the said relay from further operation after the desired portion of the said paths has been selected until the said controller is returned to the off position.

3. The combination in a selective system of control of a supply conductor, a plurality of separate paths from said conductor, electroresponsive switch mechanism for establishing a selected portion of said paths, an electro-responsive relay connected to the said conductor and operated responsively to the potential of the conductor for controlling the energization of the said switch mechanism to select the portion of the said paths from the said conductor to be established, and an electromagnetic lock energized from the said conductor for preventing further unintentional operation of the said relay after the desired portion of the said paths has been selected the said lock arranged to operate at a higher value of potential than the operating potential of said relay and maintain its locking effect at a lower value of potential than the operating potential of said relay.

4. The combination in a selective system of a control of a supply conductor, electro responsive switch mechanism for establishing a selected portion of a plurality of separate paths from the said conductor, a relay connected to the said conductor for controlling the energization of the said switch mechanism to select the desired portion of the said paths to be established, electro magnetic operating means for the said relay arranged to operate within one range of values of the potential of said conductor and be magnetically held from operating at higher values of the potential of the said conductor, and electro-responsive means for locking the said relay to prevent the unintentional operation of the same, the said locking means arranged to operate at a higher potential of the supply conductor than the said operating range of said relay and to maintain its locking effect at a potential of the supply conductor below the said operating range of potential of the said relay.

5. A reversing control system for electric motors comprising a motor supply conductor, electro-responsive reversing switch mechanism, a selector relay operated responsively to the potential of the supply conductor for controlling the said switch mechanism, a reversing controller for controlling the potential of the supply conductor to control the operation of the said relay, and an

electromagnetic lock for the said relay energized from the said conductor for preventing the unintentional operation of the same.

6. A reversing control system for electric motors comprising a motor supply conductor, a resistor, a reversing controller operable in one direction from an off position to connect the said conductor to a source of supply through the said resistor and operable in the other direction to connect the supply conductor to the source of supply with the said resistor excluded, electro-

nism, an electro-responsive selector relay operated responsively to the inclusion and exclusion of the said resistor in circuit with the said supply conductor for controlling the said reversing switch mechanism, and a normally released electromagnetically controlled lock energized from the said supply conductor for preventing the operation of the said relay except under the control of the said controller.

In witness whereof, I have hereunto set my hand this 28th day of December, 1921

EUGENE R. CARICHOFF
